BANDLESS BEATER ROLL AND JORDAN PLUG

John D. Haskell, Fulton, N. Y., assignor to Dilts Machine Works, Inc., a corporation of New York

Application February 7, 1935, Serial No. 5,488

4 Claims. (Cl. 92—22)

This invention relates to bandless beater rolls and Jordan plugs or the like, in which class of devices the roll construction is usually made up of separate heads or spiders into which the fly bars are keyed by means of wedges. The object of this invention is to provide primarily a roll of a solid drum type, although the interior may be cored out, and similarly the construction may be applied to the formation of the customary Jordan 5 plug and shaft.

In the form of construction for which a patent is now solicited, the cylinder or plug is provided with spaced milled slots of dovetail cross section, and in place of a number of individual keys or 15 wedges there is employed one long wedge-shaped spline which may be inserted either separately or with the fly bars or Jordan knives and driven endwise into the slots. This provides a bearing for the bar throughout its whole length, and it 20 may be easily removed by driving the bar and spline endwise out of the drum or plug.

One objection to present types of bandless beater rolls and Jordan plugs is that after several 25 refillings the slots or grooves become worn which necessitates the use of thicker bars or knives, making it obligatory to carry a considerable stock of various thickness steel to take care of replacements. With the construction comprised in the 30 present invention, the bars or knives may be standard at all times, but splines of varying size may be employed to take up the wear.

In the accompanying drawings illustrating this 35 invention, Fig. 1 represents in section a peripheral portion of a roll with this invention applied thereto.

Fig. 2 is a similar section of a roll with a modified form of this invention applied thereto.

Fig. 3 shows a pair of adjacent beater bars in 40 section with the required filling between them and the poured metal locking element arranged to secure the bars and filling.

Fig. 4 is a sectional view of a portion of a roll or plug showing spaced fly bars or knives constructed in accordance with this invention, and 45 showing a modified form of the arrangement of bars or knives secured to the roll, with the filling between adjacent bars, and the metal bar locking material which may be poured in from the outer 50 surface of the filling.

Fig. 5 represents in section a portion of the 55 periphery of a roll or plug showing a pair of adjacent fly bars with the wood filling between them extended somewhat beyond the periphery of the roll, and showing also the cast metal wedges at

the sides of the bars connected through the bars and wood filling to secure the bars in the roll.

Fig. 6 is a sectional view similar to Fig. 5, but showing fly bars having recesses adapted to receive and engage portions of the cast metal securing wedges, and illustrating an inverted T-shaped passage in the wood filling containing the cast metal securing material passing through the bars and joining the cast metal wedges. 5

Fig. 7 is a sectional view of a portion of a roll 10 or plug with a single fly bar of ordinary form and wood filling against the side of the bar, with the metal securing material introduced at the side of the wood filling and passing through the filling and bar and integral with the cast metal securing 15 wedge engaging the bar and roll.

Fig. 8 shows a pair of adjoining fly bars of the 20 same form as the bar shown in Fig. 7, with widened wood filling having an inverted passage of T-shape filled with the cast metal securing material passing through the wood filling, through the bars and connecting the cast metal bar holding 25 wedges at the sides of the bars.

Fig. 9 is a fragmentary perspective view of one 30 end of a fly bar of the type shown in Figs. 7 and 8, showing the wood filling against the bar, and setting forth also the spaced holes through the bar and the spaced inverted T-shaped passages in the filling which are arranged in communication 35 with the holes through the bar.

Throughout the drawings and description of 40 this invention the same number is used to refer to the same part.

Considering Figs. 1 to 4, the roll 1 has lengthwise wedge-shaped slots or grooves 2 for the bars 3 and 4. The bar 3 may be milled or rolled to give a thinner cutting edge if desired. The bars, as shown by bar 4 have the reentrant portions 5 engaged by the splines 6. It is not, however, intended to limit this invention to the particular 45 wedge-shaped formations illustrated and described, as such forms may be readily changed by those familiar with this kind of apparatus.

Considering Fig. 2 there is set out a cluster filling with splines on both sides of the knives. In 50 this figure the roll 7 has the groove 8 occupied by the knives or bars 9 and 10, with the filling piece 11 introduced between them. The continuous splines 12 are driven in on opposite sides of the 55 knives.

In Fig. 3, the bars 13 and 14, each of which has the usual reentrant portion 15 and heel 16, are separated by the wooden filling wedges 17 and 18. In this figure it will be noted that the bars are 55

provided with orifices or apertures 19, which are ordinarily round holes through the bars, but which may be oblong or rectangular as chosen, and those apertures register with the passages or 5 apertures 20 of inverted T-shape and formed in the wooden filling. Metal bar locking material 21 is poured into the apertures in molten condition and serves to lock the bars and filling securely together. The metal locking material may 10 be hard Babbitt metal or any other like material that cools quickly and will not tend to enlarge the aperture by burning the wood filling.

In Fig. 4, the roll 22 has the regular grooves 23 with bars 24 and 25 therein, secured by the continuous spline 26 as previously explained. The filling 27 between the bars has the inverted T-shaped passage or aperture filled with the metal locking material 29 in the holes through the bars as well as in the passage 28.

0 The modification shown in Fig. 5 comprises the bars 30 and 31 with the wood filling 32 projecting somewhat beyond the periphery of the roll or plug 33. The bars and filling are placed in the wedge-shaped or convergent cavity 34 in the roll, and the molten locking metal when poured in forms the side wedges 35 and 36 integrally joined by the coupling 37 of the metal which passes through the bars. The metal may be introduced by way of the side duct 38 indicated 5 in broken lines, and it will be noted that the cast wedges 35 and 36 each possesses projecting lugs such as lug 35' which engage corresponding depressions in the sides of the convergent cavity 34 in the roll.

15 Regarding the modification illustrated in Fig. 6, the fly bars 39 and 40 are inserted in the convergent cavity 41 of the roll or plug 42, with the wood filling 43 between the bars. In this form of the invention the Babbitt metal 44 is poured into 40 an inverted T-shaped passage in the filling 43, and passes through the bars to the left and right forming the side wedges 45 and 46 joined by the integral coupling 47. The filling 43 projects for a distance beyond the periphery of the 45 roll or plug.

Respecting the modification set out in Fig. 7, the fly bar 48 occupies the convergent cavity 49 in the roll or plug 50, wood filling 51 being arranged on one side of the bar. The cast locking 50 metal 52 fills an L-shaped passage in the roll at the side of the filling and passes through the filling and bar forming the side wedge of cast metal 53, engaging the reentrant portion of the bar as illustrated.

15 Considering Fig. 8 the bars 54 and 55 are located in the convergent cavity 56 of the roll or plug 57, and the wood filling 58 between the bars extends somewhat beyond the surface of the roll. The Babbitt metal lies in inverted T-shaped form 0 in a corresponding passage in the filling 58, the metal 59 passing through the bars to the left and right thereby casting the side locking wedges 60 and 61.

In the explanatory Fig. 9, the fly bar 54 has 5 spaced holes 62 and 63, and the wood filling 58 has

the inverted T-shaped passage comprising the vertical portion 64 for the introduction of the Babbitt metal in molten condition, and the transverse passage portion 66 which as shown registers with the hole 62 through the fly bar 54. Filling 58 has a second passage for the babbitt comprising the entrance portion 65 and the transverse portion 67 registering with the hole 63 in the bar. As many spaced bar holes and filling passages as may be needed are contemplated in the purview 10 of this invention.

In the practice of this invention, it will be noted that the fly bars may be doubly secured, in one instance by the use of the continuous splines, and additionally by the cast metal locking material. Or, the locking metal may be arranged as shown in the several modifications to adequately secure the bars.

When need arises, the bars can be removed with the splines by using a chisel to chip out the 20 wood filling, and then driving out the bars and splines endwise.

Having now described this invention and the manner of its use, I claim:—

1. In a beater roll or the like, the combination 25 with a roll having spaced grooves, beater bars arranged in the grooves, filling between the bars, the said filling and the said bars having registered apertures extending to the outer surface of the filling, and metal bar locking material cast 30 in position in said apertures whereby the bars are secured in place with the filling.

2. In a beater roll or the like, the combination 35 with a roll having spaced grooves, beater bars arranged in the grooves, filling between the bars, 40 the said grooves and bars and filling having wedge-shaped mutually engaging portions whereby the bars are held in place, the said filling having an inverted T-shaped aperture extending to the outer surface of the filling, the said bars 45 having apertures registering with the apertures of the filling, and metal bar locking material cast in position in the apertures whereby the bars and filling and roll are locked together.

3. In a beater roll or the like, the combination 45 with a roll having lengthwise peripheral convergent grooves, fly bars located in the grooves, filling between the bars, said bars and filling being provided with registering passages, and material cast in position in the said passages and 50 arranged to form integral side wedges between said bars and said convergent grooves.

4. In a beater roll or the like, the combination 55 with a roll having lengthwise peripheral convergent grooves, fly bars located in the grooves, filling between the bars, said bars and filling being provided with registering passages, material cast in position in the said passages and arranged to form integral side wedges between said bars and said convergent grooves, said cast wedges 60 having projections at the sides, and the said grooves being constructed to engage the said projections.

JOHN D. HASKELL.
